(57) **CLAIM**

The ornamental design for a boot, as shown and described.

DESCRIPTION

FIG. 1 is a top perspective view of a boot showing our new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a top perspective view thereof showing the gussets unzipped.

The heavier-weighted, dashed seam edge lines shown on the boot upper depict stitching, which forms no part of the claimed design. Portions of the boot illustrated in the lighter-weighted, dotted lines form no part of the claimed design.
